UNITED STATES PATENT OFFICE.

KATHERINE J. STUMP AND CHRISTOPHER W. STUMP, OF WASHINGTON, DISTRICT OF COLUMBIA.

CONVERTIBLE TRUNK AND BED.

992,616.

Specification of Letters Patent. Patented May 16, 1911.

Application filed November 28, 1910. Serial No. 594,546.

To all whom it may concern:

Be it known that we, KATHERINE J. STUMP and CHRISTOPHER W. STUMP, citizens of the United States, residing at Washington, in the District of Columbia, have invented certain new and useful Improvements in Convertible Trunks and Beds, of which the following is a specification.

This invention comprises an improved convertible trunk and bed, and its primary object is to provide a portable article of the above class of exceedingly simple construction, and which may be readily transformed from a trunk into a bed, or vice versa. 10
15 In carrying out the invention, an especial object is to obtain a construction possessing a maximum degree of rigidity, and yet comparatively light to avoid undue weight when the invention is used as a trunk. 20
25 The invention is especially advantageous for use for traveling purposes, by campers, and for general service where a trunk or quickly foldable bed would be advantageous. For a full understanding of the present invention, reference is to be had to the following description and to the accompanying drawings, in which—

Figure 1 is a perspective view of the invention with the parts as arranged as when used as a bed, the canopy being thrown open to disclose the interior construction; Fig. 2 is a vertical longitudinal sectional view of the invention showing the canopy operatively arranged to extend entirely over the bed; Fig. 3 is a top plan view, partly broken away, and shown in section, the parts of the invention being adjusted to form a trunk; Fig. 4 is a vertical longitudinal section of the device as shown in Fig. 3; Fig. 5 is a transverse section taken about on the line 5—5 of Fig. 4; Fig. 6 is a plan view of the canopy, which may be used in connection with the invention; Fig. 7 is a fragmentary detail view showing one of the hasp plates carried by the sides and bottom of the trunk; Fig. 8 is a detail view of one of the locking rods; Fig. 9 is a detail perspective view of one of the foot pieces; Fig. 10, is a fragmentary view of an end of one of the slats of the spring; and Fig. 11 is a sectional view of a portion of the spring. 30

Throughout the following description and

on the several figures of the drawings, similar parts are referred to by like reference characters.

In the preferred embodiment of the invention, it is contemplated that its parts may be arranged to provide a trunk of the same general form as ordinarily in use, and comprising sides 1 hinged to the bottom 2, ends 3, and a cover or lid 4.

The above parts when closed together, as shown in Figs. 3 to 5 inclusive, provide a box like structure or trunk, and when adjusted, as shown in Fig. 1, the sides 1 and bottom 2 constitute the body of a bed, the cover 4 affording the head piece, and the ends 3 providing side members convenient for use with the head 4 to support a canopy 5 should it be wished to employ the latter, 70 as desirable when the invention is used as a bed out of doors.

When used as a trunk, the parts of the invention are held in their closed or folded condition by means of hasp plates 6 attached to the sides 1, and having slots to receive staples 7 on the inner sides of the ends 3. Locking rods 8 are adapted to pass through the staples 7 and outer sides of the plates 6 whereby to prevent disengagement 80 of said plates from the staples. Said locking rods have lateral extensions 8' at their upper ends to overlap the upper edges of the ends 3 of the trunk, to limit the downward movement of said rods, and afford convenient finger pieces for ready attachment and detachment of the latter. Hook rods 9 are preferably employed to connect the cover 4 with the ends 3 when the trunk is unfolded to provide a bed, as shown in Fig. 1, said 90 hook rods being pivoted to the cover 4, and their hooks being adapted to engage certain of the staples 7 on ends 3.

A spring or cushion is provided for the bed when in use, and preferably comprises 95 yieldable side and bottom members 10 applied to the sides 1, and bottom 2 of the trunk. The members 10 preferably consist of slats supported on coiled springs 11 and connected in a flexible manner by means of 100 wires 12. The parts 10 take up very little room, and if desired, a mattress or auxiliary cushion 13 may be placed thereon, as shown in Fig. 2, though the yieldability of the

parts 10 permits of ready use thereof without the mattress or cushion 13, by placing the bed directly upon said slats 10.

Transverse cleats 14 may be applied to the 5 ends 3 to support a tray 15, when the invention is used as a trunk, said tray to contain any suitable articles. Even with the use of the tray 15, ample room will be left when the trunk is folded ready for use to permit 10 of placing bedding, etc., in said trunk.

The canopy 5 is somewhat peculiar in that it is secured at one end, as shown at 5', to the outer edge of one of the sides 1, and said canopy may be provided at its edges with 15 openings to fit over buttons or similar fastenings applied to the upper edges of the ends 3 and cover 4.

The canopy will be made preferably as shown in Fig. 6, with suitable extensions to 20 extend downwardly on opposite sides of the ends 3, in the manner shown in Fig. 2. When the invention is used as a trunk, the canopy 5 will be folded to provide a lining for the trunk, extending over the yielding 25 members 10, as illustrated clearly in Figs. 4 and 5.

Supporting legs 16 are provided on the ends 3 and other supporting legs 17 are provided on the sides 1. The legs 16 are preferably rigid with an edge panel 16' at the 30 lower edge of each end 3, said panel 16' being hinged to the end 3 and adapted to fold downwardly to carry the legs 16 in vertical positions, to support the invention when 35 used as a bed. The legs 16, when folded upwardly against the ends 3 form crossed panels coacting with the panel 16' and permanent panel 16'' to afford paneling for the ends 3, and at the same time bracing said 40 ends.

The legs 16 have foot pieces 19 which are really spring members adapted to engage over the upper edges of the ends 3 to hold the legs against the outer sides of the ends. 45 The upper edges of the ends may be rabbed, or recessed, as at 19' to receive the foot pieces 19, in an obvious manner.

The legs 17 are carried rigid with a hinged edge panel or strip 20, one of which is 50 pivoted to the outer longitudinal edge portion of each side. The legs 17 are adapted to fold against the outer surfaces of the sides 1 and at their lower portions, said legs are provided with catches 21 adapted 55 to pass through openings near the hinges 22, by which the sides 1 are connected with the bottom 2. The catches 21 detachably connect the legs 17 with the parts 1 when the parts of the invention are folded to provide 60 a trunk, and also affords a bracing function as above mentioned.

When the device is folded to form a trunk, should it be desired to provide a bed, the cover 4 is unlocked and raised, and the

rods 8 are removed from the staples 7, permitting the hasp plates 6 on the sides 1 to be disengaged from said staples, and the sides moved downwardly into alignment with the bottom. The hook rods 9 are then connected with the ends 3 to support the 70 cover 4 as a head piece, after which the foot piece 19 and catches 21 may be readily manipulated to disengage the same from the parts 3 and 1 respectively. The legs 16 and 75 17 are then placed in vertical positions to support the bed comprised by the sides 1 and bottom 2. The tray 15 is displaced in using the invention as a bed, and it is to be understood that the trunk above described may be made in various sizes as found most 80 desirable under practical conditions of service.

In reference to the cushion formed by the slats or members 10, to facilitate folding of the same when the invention is used as a 85 trunk, certain of the slats designated 10' arranged above the sides 1, when the invention is used as a bed, will be loosely mounted so that they may be turned into positions shown in Fig. 5, to rest on the slats 10 of 90 the bottom 2. When the cushion is arranged as shown in Fig. 1, the slats 10' will be detachably connected by fastenings 10'' with adjacent slats 10 of the sides 1. The detachable connection 10'' is necessary in 95 order to permit of folding of the cushion or spring part of the bed when the invention is converted from a bed to a trunk.

Having thus described the invention, what is claimed as new is:

1. In a convertible trunk and bed, the combination of a bottom, sides and ends, edge panels carried by the sides and ends and pivotally connected therewith, crossed panels carried by the edge panels aforesaid and constituting legs movable into operative positions to support the article when the parts are adjusted to form a bed, and foot-pieces comprising spring members to engage over the sides and ends and hold the 110 panels or legs against the same when the article is folded to form a trunk.

2. In a convertible trunk and bed, the combination of a bottom, sides hinged thereto, ends, and a cushion comprising yieldable 115 members applied to the bottom and sides and housed thereby when the structure is folded to form a trunk, the yieldable members of the cushion embodying a plurality of slats arranged edge to edge, springs supporting 120 said slats, and detachable fastening means between adjacent slats on the sides and bottom of the bed, whereby the detachable slats of the sides may be folded on to the slats of the bottom to facilitate folding and converting the invention into a trunk.

3. In a convertible trunk and bed, the combination of a bottom, sides hinged

thereto and movable into positions in alignment with the bottom to provide a bed, and a cushion carried by the sides and bottom and comprising a plurality of yieldable members arranged edge to edge, the yieldable members being flexibly connected together, certain of said yieldable members being detachable adjacent to the points of hinged connection of the bottom and sides, to permit the latter to be folded when the parts

of the article are adjusted to provide a trunk.

In testimony whereof we affix our signatures in presence of two witnesses.

KATHERINE J. STUMP.
CHRISTOPHER W. STUMP.
